UNITED STATES PATENT OFFICE.

JOSEPH E. LARSON, OF SILVERCREEK, NEBRASKA.

BROOM-CORN HARVESTER.

SPECIFICATION forming part of Letters Patent No. 716,440, dated December 23, 1902.

Application filed August 15, 1902. Serial No. 119,728. (No model.)

To all whom it may concern:

Be it known that I, JOSEPH E. LARSON, a citizen of the United States, residing at Silvercreek, in the county of Merrick and State 5 of Nebraska, have invented certain new and useful Improvements in Broom-Corn Harvesters; and I do declare the following to be a full, clear, and exact description of the invention, such as will enable others skilled in 10 the art to which it appertains to make and use the same.

This invention relates to broom-corn harvesters, and particularly to those in which the stems of the heads or brushes are cut to 15 a proper or desired length before being discharged from the machine.

A further object is to construct a machine of the character described that will be comparatively simple in construction, durable in 20 use, efficient, and well adapted to the purpose for which it is designed.

With the above and other objects in view, which will readily appear as the nature of the invention is better understood, said invention 25 consists in certain novel features of construction and combination and arrangement of parts, which will be hereinafter fully described and claimed, and illustrated in the accompanying drawings, in which—

30 Figure 1 is a view of one side of the machine. Fig. 2 is a view of the opposite side thereof. Fig. 3 is a top plan view. Fig. 4 is a front end elevation. Fig. 5 is a transverse vertical section through the straightening-rolls and the delivery-apron on line 5 5 of Fig. 1. Fig. 6 is a longitudinal vertical section taken through the cutter-bar, reel, and conveyer and straightening-rolls, as indicated by dotted line 6 6 of Fig. 3.

35 40 1 denotes the main supporting-frame of the machine, which consists of the side bars 2 and a centrally-disposed bar 3, connected at their ends by cross-bars 4.

45 50 5 denotes a main carrying and power-transmitting wheel mounted upon a shaft or axle 6, journaled in bearings formed on one of the side bars 2 and the central bar 3 near the forward end of the machine.

7 denotes the carrying-wheel, forming the 55 companion of the wheel 5, journaled upon a stub-shaft formed on a depending arm or

bracket fixed to the side bar opposite the wheel 5.

8 denotes the rear easter-wheel, pivotally connected to the rear cross-bar of the frame. 55

9 denotes an auxiliary frame supported by standards 10, fixed at their lower ends to the main frame 1. The frame 9 is designed to carry at its forward end the cutter-bar 11 and sickle 12. Sides or guards 13 are mounted 60 upon the frame 9 and have at their forward ends forwardly-extending divergent arms 14, which are adapted to gather in the stalks as the machine moves forward.

15 denotes a reel mounted in the upper 65 ends of inclined supports 16, which are adjustably connected at their lower ends to the side pieces or guards 13.

17 denotes an endless slatted conveyer or apron which runs over rollers journaled in the 70 frame 9 immediately in rear of the cutter-bar 10 and between the side pieces or guards 13.

18 denotes a frame arranged across the machine immediately in rear of the frame 9 and is supported by the standards 10 and 10^a and 75 is slightly inclined from the frame 9 toward the opposite side of the machine. The frame 18 is divided transversely and longitudinally by bars 19 and 20, and in the part of the frame immediately in rear of the conveyer 80 17 are mounted straightening-rolls 21, arranged in a direction across the line of travel of the endless conveyer 17 and are journaled in the outside cross-piece of the frame 18 and the division strip or bar 20. The ends of the 85 roll-shafts journaled in the side cross-piece project beyond the same and are provided with sprocket-pinions 22. The rolls 21 are spaced apart and are provided along their length with cleats.

90 23 and 24 denote guard-aprons connected to a portion of the frame and form practically a continuation of the guards 13.

25 denotes a bar arranged in rear of the conveyer 17 and above the straightening-rolls, 95 and 26 denotes spring-fingers connected to said bar and depending therefrom and are adapted to assist in straightening and arranging the heads or brushes of the corn.

27 denotes "packers," consisting of narrow 100 blades or fingers, which are adapted to work between the rolls 21 to push the heads across

the said rolls. The packers or blades are mounted upon a cranked shaft 27^a, arranged longitudinally of the machine beneath the rolls 21 and journaled at its ends in bearings 5 formed on the standards 10 and 10^a and pivoted on its rear or outer end with a band-wheel 28. The packer-blades extend some distance below the crank-shaft and are connected to one of the side bars 2 of the main 10 frame by links 29.

The space in the frame 18 on the opposite side of the division-bar 20 is covered by a solid platform 30, and a guard-flange 31 is formed on the rear side of said platform.

15 32 denotes an endless slatted conveyer or delivery-apron arranged above the platform 30. The said conveyer passes around rolls 33 and 34, mounted in suitable bearings carried by the frame 18, the shaft of the roll 33 20 being extended and provided with a band-pulley 35, which is connected by a cross-belt 36 to the band-wheel 28, by which means the conveyer 32 is driven.

In the space formed in the frame 18 by the 25 transverse division-bar 19 is arranged a cutting-wheel 37, adjustably mounted upon a shaft 38, arranged across said space and journaled in bearings carried by the said frame.

30 39 denotes a plate or strip of metal adjustably mounted upon the platform 30 adjacent to the cutting-wheel 37, the edge of said plate acting, in conjunction with said wheel, to form a shear for cutting the stems of the heads or brushes to the desired length. By adjusting 35 the plate and cutting-wheel different lengths of stems may be obtained.

On the outer end of the shaft 38 is fixed a spur gear-pinion 40, which is in mesh with and driven by a spur gear-wheel 41, fixed on 40 a shaft 42, mounted at one end in bearings carried by the frame 18 and at its opposite end in bearings carried by an arm fixed to the standards 10.

43 denotes a sprocket-pinion mounted upon 45 the shaft 42 and is connected to a sprocket-pinion 44, fixed on the inner end of the cranked shaft 27^a.

45 denotes a sprocket-pinion, also mounted on the shaft 42.

50 Upon the axle 6 of the main drive-wheel is mounted a combined bevel and spur gear-wheel 46.

47 denotes a short shaft journaled in brackets carried by the main frame 1. On the inner end of the shaft 47 is fixed a bevel gear-pinion 48, which is in mesh with the bevel gear of the wheel 46, and on the opposite end of the shaft 47 is mounted a sprocket-wheel 49.

50 denotes a short shaft mounted in bearings supported upon an arm or bracket carried by the frame 9. On the outer end of the shaft 50 is formed a crank, to which is connected a pitman-rod 51, which is connected at its opposite end with the sickle-bar.

65 On the opposite end of the shaft 50 is fixed a sprocket-wheel 52, which is connected to the wheel 49 by a sprocket-chain 53, whereby the

sickle-bar is driven. One of the stretches of said chain is in engagement with the sprocket-wheel 45, mounted on the shaft 42, by means of which said shaft is driven and in turn drives the cutting-wheel 37 and the crank-shaft 27^a, from which motion is imparted to the endless conveyer 32.

54 denotes a spur gear-pinion mounted upon the inner end of a shaft 55, journaled in bearings carried by the frame 1, the said pinion 54 being in mesh and driven by the spur gear-teeth of the wheel 46. On the opposite end of the shaft 55 is mounted a double sprocket-wheel 56.

57 denotes a sprocket-pinion fixed on the shaft 58 of the inner roll of the conveyer 17, said pinion being connected with the larger wheel of the double sprocket-wheel 56 by a 85 chain 59, whereby the conveyer 17 is driven.

60 denotes a band-pulley, also fixed to the shaft 58 and driven thereby.

61 denotes a band-wheel fixed on the end of the reel-shaft of reel 15, and the said wheel 90 is connected with the band-pulley 60 by a crossed belt 62, by which means the reel is driven.

63 denotes a sprocket-chain which connects the smaller wheel of the double sprocket-wheel on the shaft 55 with the sprocket-pinions 22 on the straightening-rolls, by which means the said rolls are driven.

64 denotes a delivery-fork fixed on an arm connected to a rock-shaft 65, supported in bearings beneath the outer edge of the frame 18, adjacent to the discharge end of the conveyer or delivery-apron 32, said fork being adapted to receive the straightened and trimmed heads of the corn from the platform 30. The forward end of the shaft 65 is bent at right angles to itself to form a crank 66, to the inner end of which is connected one end of a chain 67, which passes under a guide-pulley and is connected at its free end with an operating-lever 68, by which the fork 64 may be raised and lowered to discharge the heads at intervals or as desired.

69 denotes the driver's seat, mounted upon the frame 1, and 70 denotes a bar to which 115 the tongue draft devices (not shown) are attached. The upper end of said bar is connected to the end of a lever pivoted to the standard 10 and having an adjustable pawl-and-rack connection with the said standard, 120 by means of which the draft of the machine may be raised or lowered.

In operation the machine is intended to be driven through a field of standing corn, the diverging arms 14 being adapted to gather in 125 a row of stalks similar to the ordinary corn-harvesting machines and to conduct them to the cutting apparatus, where the heads are severed from the stalks, the reel also aiding in knocking the heads back against the 130 knives. After the heads are cut off they fall back upon the conveyer 17 and are carried rearwardly and deposited upon the rolls, where they are acted on by the said rolls,

packers, and spring-fingers 26 and straightened out and forced upon the platform 30, with their ends projecting forwardly and in position to be trimmed off by the cutting-wheel to the proper length, the heads being forced along the platform by means of the endless slotted belt 32 and discharged upon the delivery-fork, from which they are dumped at the will of the driver.

10 From the foregoing description, taken in connection with the accompanying drawings, it is thought that the construction, operation, and advantages of my improved broom-corn harvester will be readily apparent without requiring a more extended explanation.

Various changes in the form, proportion, and the minor details of construction may be resorted to without departing from the principle or sacrificing any of the advantages of this 15 invention.

Having thus described my invention, what I claim as new, and desire to secure by Letters Patent, is—

1. In a machine for harvesting broom-corn, 20 the combination of a main wheeled frame, of an auxiliary frame carried by said main frame, gathering and cutting mechanism carried at the forward end of said auxiliary frame for cutting the heads from the standing corn, 25 straightening-rolls, an endless conveyer for conveying the gathered heads from the gathering mechanism to the straightening-rolls, spring-fingers for aiding in straightening said heads, packing-blades for pushing said heads 30 across the rolls and onto a table or platform, an endless conveyer arranged above said platform to convey the heads across said platform, a cutting-wheel arranged to trim off the stems of said heads, gearing for operating 35 the several parts, and a delivery-fork for discharging said trimmed heads, substantially as described.

2. In a machine of the character described, 40 the combination of a main wheeled frame of

an auxiliary frame carried by said main frame, 45 gathering mechanism, a reciprocating sickle-bar arranged in rear of said gathering devices, an endless conveyer arranged in rear of said sickle-bar, straightening-rolls mounted in rear of said endless conveyer, spring-fingers 50 adapted to aid said rolls, a table or platform, packing-blades, adapted to operate between said rolls, to force the heads upon said platform, a second endless conveyer arranged above said platform for moving the heads 55 across the same, an adjustable cutting-wheel, and an adjustable shear-plate for cutting the stems of the broom-corn heads at various lengths, a delivery-fork for receiving the trimmed heads from the said platform, means 60 for operating said delivery-fork to discharge said heads, and gearing for operating the several parts, substantially as described.

3. In a machine of the character described, 65 the combination of a reel, divergent gathering-arms for gathering the heads, a cutting apparatus in the rear of said gathering-arms for cutting off said heads, straightening-rolls, an endless conveyer for conducting the heads from said cutting apparatus to said straightening-rolls, packing-blades for aiding in straightening and pushing said heads across said rolls, means for operating said packing-blades, a cutting-wheel, means for conducting the heads from said rolls across the path 70 of movement of said cutting-wheel, a delivery-fork for receiving and discharging the heads after being trimmed, and gearing for operating the several parts, substantially as described. 75

In testimony whereof I have hereunto set my hand in presence of two subscribing witnesses.

JOSEPH E. LARSON.
